UNITED STATES PATENT OFFICE.

JOSEPH H. KEVORKIAN, OF PHILADELPHIA, PENNSYLVANIA.

BACK-REST FOR DISPLAY-CARDS, &c.

SPECIFICATION forming part of Letters Patent No. 730,027, dated June 2, 1903.

Application filed March 6, 1901. Serial No. 50,030. (No model.)

To all whom it may concern:

Be it known that I, JOSEPH H. KEVORKIAN, a citizen of the United States, residing at the city and county of Philadelphia and State of Pennsylvania, have invented certain new and useful Improvements in Back-Rests for Display-Cards, &c., of which the following is a full, clear, and exact description, reference being had to the accompanying drawings, forming a part of this specification.

The object of this invention is to provide a simple, cheap, and efficient back-rest for display-cards and other articles, the device, as generally stated, comprising a basal portion attachable to the card, &c., a support hingedly connected with such portion, so that it (the support) may be folded against or swung outward from the card, &c., and a brace hingedly connected with such basal portion and having a sliding connection with the support, whereby the brace may be folded with the support or be swung outward with the latter in a manner to rigidly sustain the same in supporting position.

This invention also comprises details of construction, which will be hereinafter particularly pointed out.

In the drawings, Figure 1 is an edge view of a display-card or the like provided with my improved back-rest. Fig. 2 is a rear elevation thereof. Fig. 3 is a view similar to Fig. 1, but with the back-rest folded thereon. Fig. 4 is a rear elevation of Fig. 3. Fig. 5 is a cross-section, as on the line 5 5 of Fig. 1.

A represents a display-card or other analogous device to be supported in an inclined position, and B represents my improved back-rest therefor. This back-rest comprises a basal strip b, a support b', and a brace b''. The strip b is composed, preferably, of a single piece of sheet metal or other suitable material, with its extremities curled outward to form transverse eyes b³. This strip is adapted to be fastened in a vertical position along the back of the card, the fastening being preferably effected by means of a piece of paper b⁴ or the like imposed on and cemented to the strip and card. The support is composed of a single piece of wire bent to form a transverse member b⁵, which is pivoted in the upper eye of the strip, two depending side members b⁶, which slightly diverge from the ends of the

member and extend somewhat below the lower end of the strip, two inwardly-turned portions b⁷, a connected or twisted portion b⁸, and two diverging portions b⁹, which terminate at their lowermost extremities in loops or feet b¹⁰. The brace is also composed of a single piece of wire bent into U shape, the transverse member thereof being pivoted in the lower eye of the basal strip and the side members being provided at their free extremities with elongated eyes b¹¹, through which loosely extend the side members of the support, so that the brace and support will have a free sliding connection with each other. By this construction it will be seen that if the brace be swung outward from the back it will carry therewith the swinging support in a manner to maintain the latter in the supporting position, as illustrated in Figs. 1 and 2, and if, on the other hand, the brace be folded upward against the back it will likewise carry therewith the support, as shown in Figs. 3 and 4. The extremities of the brace, in which the eyes are formed, are bent slightly outward, as indicated most clearly at x in Fig. 3, so that when the parts are folded the support will be close against the back of the card and embrace the brace.

It will be observed that when the back-rest is in open position the eyes of the brace engage and interlock with the corners y of the support, so as to render the structure stable and avoid its accidental collapse. To aid still more effectually in this respect the brace when the rest is open inclines downwardly from the back to the support.

I claim—

1. A back-rest comprising a basal portion, a support hinged thereto including a transverse member b⁵, two depending side members b⁶, and two inwardly-turned members b⁷, having locking-corners y; a brace composed of a single piece of wire bent into U shape, the transverse member thereof being pivoted to the basal portion and the side members being provided with eyes through which loosely extend the side members of the said support, which eyes are adapted to engage and interlock with the said corners when the back-rest is in open position.

2. A back-rest comprising a basal portion, a support hinged thereto composed of a single

piece of wire bent to form the transverse member b^5 , two depending side members b^6 , two inwardly-turned portions b^7 , having locking-corners y , a connected or twisted portion b^8 , 5 and two diverging portions b^9 ; a brace composed of a single piece of wire bent into **U** shape, the transverse member thereof being pivoted to the basal portion and the side members being provided with eyes through 10 which loosely extend the side members of the

said support, which eyes are adapted to engage and interlock with the said corners when the back-rest is in open position.

In testimony whereof I have hereunto affixed my signature in the presence of two subscribing witnesses.

JOSEPH H. KEVORKIAN.
